Primary Examiner — Austin Murphy(74) **Attorney, Agent, or Firm** — Banner & Witcoff, Ltd.(57) **CLAIM**

The ornamental design for a dustpan, as shown and described.

DESCRIPTION

FIG. 1 is a top, front, right perspective view of a dustpan showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines immediately adjacent to the shaded area represent unclaimed boundaries of the design. The broken lines showing the remainder of the dustpan are for environmental purposes only and form no part of the claimed design.

1 Claim, 5 Drawing Sheets
